UNITED STATES PATENT OFFICE.

GEORGE SPENCE, OF TORONTO, CANADA.

CARBON-COPY LETTER-BOOK.

SPECIFICATION forming part of Letters Patent No. 737,035, dated August 25, 1903.

Application filed April 10, 1902. Serial No. 102,288. (No model.)

To all whom it may concern:

Be it known that I, GEORGE SPENCE, of the city of Toronto, in the county of York, Province of Ontario, Canada, have invented certain new and useful Improvements in Carbon-Copy Letter-Books, of which the following is a specification.

My invention relates to that class of letter-book in which copies of letters written may be made and kept by the use of carbon-paper; and my object is to devise simple, effective, and convenient means for holding the letter and carbon-sheet in place when the book is being used.

With this object in view my invention consists in the peculiar construction, arrangement, and combination of parts, substantially as hereinafter more particularly described and then definitely claimed.

Figure 1 is a perspective view of my letter-book, showing a letter-sheet held in position. Fig. 2 is a similar view showing a letter-sheet partly removed and showing also the copy. Fig. 3 is an enlarged perspective detail showing one of the spring-holders with its finger in the position which it assumes when engaged with a letter-sheet. Fig. 4 is a similar view showing the holder with its finger in the position it assumes when disengaged.

In the drawings like letters of reference indicate corresponding parts in the different figures.

In Figs. 1 and 2, A is the cover of the book, and B the leaves. While a full cover is shown, it must be understood that the only essential part of the cover is that to which are connected the spring-arms C. It may be further stated that it is not essential that the leaves be permanently bound with the cover, as any detachable form of binding may be used equally as well. The spring-arms C are secured to the cover, one at each side of the leaves B, preferably by means of rivets, as indicated in Fig. 4, though other means might also be employed. At or near the end of each spring-arm is pivoted a finger D. The spring-arms and fingers together form what may be

termed "spring-holders," for the purposes hereinafter described. Each finger is preferably provided with a shoulder a, so placed as to engage the arm, as indicated in Fig. 4, to limit the outward swing of the pivoted finger, so that it will not under any circumstances project sidewise beyond the cover. (See Fig. 2.) I do not wish to limit myself to the exact arrangement of this finger, as probably other means might be devised by which the finger could be engaged with a letter-sheet, as shown in Fig. 1, or disengaged, as shown in Fig. 2. In these figures, E represents a sheet of carbon-paper, F a sheet of letter-paper, and G a sheet of blotting-paper.

When it is desired to secure a copy of a letter, a sheet of carbon-paper is placed upon one of the leaves of the book. A letter-sheet is then placed over this and the spring-holders engaged with the upper surface of the letter-paper. When the letter is written, (preferably with a somewhat hard pen,) a good copy is secured in the book, as shown in Fig. 2. When writing it is preferable to keep a sheet of blotting-paper, such as G, beneath the hand to prevent the smudging of the copy. After the letter is written the spring-holders are disengaged, as shown in Fig. 2, and the letter removed, leaving the copy in the book.

Although it is preferable to use two spring-holders, as shown, yet a considerable measure of utility could be obtained by the use of one only, in which case it might be preferable to make the finger D somewhat longer than is shown in the drawings.

What I claim as my invention is—

1. A carbon-copy letter-book provided with a cover and copy-leaves, two spring-arms, one located at each side of one-half of the cover, each secured at one end to the cover with its free end adjacent to the back and provided at said free end with a pivoted finger which may be engaged with, or disengaged from, the leaves at each side adjacent to the back, substantially as described.

2. A carbon-copy letter-book provided with a cover and copy-leaves, two spring-arms, one

located at each side of one-half of the cover, each secured at one end to the cover with its free end adjacent to the back and provided at said free end with a pivoted finger which 5 may be engaged with, or disengaged from, the leaves at each side adjacent to the back, a shoulder being formed on the pivoted end of the finger and adapted to engage the arm to

limit the outward swing of the finger, substantially as described.

Toronto, March 31, 1902.

GEORGE SPENCE.

In presence of—

JOHN G. RIDOUT,
J. M. WEBSTER.
